UNITED STATES PATENT OFFICE

94,006

DESIGN FOR A SHOE

Samuel Weinstat, New York, N. Y., assignor to Scholnick Shoe Co., Jamaica Plain, Mass., a corporation of Massachusetts

Application October 18, 1934, Serial No. 53,671

Term of patent 3½ years

To all whom it may concern:

Be it known that I, SAMUEL WEINSTAT, a citizen of the United States, residing at New York, in the county of New York and State of New York, have invented a new, original, and ornamental Design for a Shoe, of which the following is a specification, reference being had to the accompanying drawing, forming a part thereof, in which

Fig. 1 is a view in perspective of a shoe showing my new design, as seen from the left side; and

Fig. 2 is a similar view as seen from the right side.

I claim:

The ornamental design for a shoe substantially as shown and described.

In testimony whereof, I have affixed my signature hereto.

SAMUEL WEINSTAT.
